YORK, N. Y., A CORPORATION OF NEW YORK.

TELEPHONE-EXCHANGE SYSTEM.

1,426,818.

Specification of Letters Patent. Patented Aug. 22, 1922.

Application filed December 28, 1918. Serial No. 268,665.

To all whom it may concern:

Be it known that we, HENRY P. CLAUSEN and CHARLES L. GOODRUM, citizens of the United States, residing at Mount Vernon, 5 in the county of Westchester and State of New York, and at New York, in the county of New York and State of New York, respectively, have invented certain new and useful Improvements in Telephone-Exchange 10 Systems, of which the following is a full, clear, concise, and exact description.

This invention relates to improvements in telephone exchange systems and has particular reference to an improved arrangement for controlling the operation of selectively operable switching devices employed 15 in machine switching systems.

In automatic systems, false setting of switches is often due to the calling subscriber 20 operating his impulse sending device before a trunk has been seized leading to a selector switch designed to receive said impulses. This results in the switch being incorrectly set and a wrong number called.

An object of this invention is to avoid the calling of a wrong number by preventing the operation of a switch should a subscriber manipulate his impulse sending device before the circuit, over which the impulses are to be transmitted to said switch, 25 is complete. In accordance with this object, each selector switch is provided with means which remains effective while the switch is in normal position, but which is rendered ineffective upon the first step of 30 the switch under certain conditions. Another means preferably similar to that at the selectors is placed at the sending device and remains inactive until said device is actuated.

The line relays of the selector switches are 35 adjusted to operate when one of said means is effective but will not energize when both are simultaneously effective. Therefore, should the subscriber operate his dial before 40 a trunk leading to a selector switch which has been seized, the means at the sending device is made effective, and upon seizure of said trunk, the means at said switch will also be rendered effective with the result that 45 the line relay of the switch will not energize, the set of impulses from the sending device will be lost and a connection will not be established with a terminal leading to a called line.

The inventive idea involved is capable of 55 receiving a variety of expressions one of which, for the purpose of illustrating the invention, is shown in the accompanying drawings; but it is to be expressly understood that said drawings are employed 60 merely for the purpose of facilitating the description of the invention as a whole and not to define the limits thereof, reference being had to the appended claims for this purpose.

In the drawings, Fig. 1 is a diagrammatic illustration of a calling substation, a line finder and a selector switch. Fig. 2 illustrates diagrammatically a connector switch and a called substation.

It is believed that the invention will be best 70 understood from a detailed description of the operation in establishing a connection between a calling and a called substation. The subscriber at substation A, by removing his receiver from its switchhook, completes 75 a circuit for line relay 100 of the line finder B extending from grounded battery, left winding of relay 100, outer armature and back contact of cut-off relay 101, substation apparatus A, impulse sending device C, conductor 102, contacts 103, conductor 104, back contact and inner armature of relay 101 and right winding of relay 100 to ground. The energization of relay 100 completes a circuit 80 from grounded battery, left winding of said relay, outer armature and back contact of relay 101, conductor 105, contact spring 106, back contact and left armature of relay 107, and winding of relay 108 to ground. Relay 85 108, by attracting its left-hand armature 90 completes a locking circuit for itself, which is independent of the left armature and back contact of relay 107. In attracting its right armature, relay 108 completes a circuit from grounded battery, winding of relay 109, slow-to-release relay 109, right armature 95 and front contact of relay 108 to ground. Relay 109, by attracting its right armature, completes a circuit for relay 107 extending from grounded battery, winding of relay 107, right armature and front contact of relay 109 to ground. Relay 107 energizes 100 and at its right-hand armature maintains the release circuit of the line finder B open during the operation of this switch. Relay 109 at its left armature completes 105 a circuit from grounded battery, winding of primary stepping magnet 110, side-

2

switch wiper 111 in its first position, back contact and armature of secondary stepping magnet 112, armature and back contact of magnet 110, armature and back contact of release magnet 113, side-switch wiper 114 in its first position, left armature and front contact of relay 109, right armature and front contact of relay 108 to ground. Primary magnet 110 interrupts its own circuit and continues to operate until the wiper 115 engages the contact 116 associated with the group of lines containing the calling subscriber's line. When so engaged, a ground will be found on said contact which completes a circuit from grounded battery, winding of primary magnet 110, winding of escape magnet 117, side-switch wiper 118 in its first position, wiper 115, contact 116, right armature and front contact of relay 108 to ground. Primary magnet 110 is maintained energized by the current flowing through this circuit, thereby preventing further stepping of the switch in the primary direction. Escape magnet 117 is also energized by this circuit and upon its energization moves the side-switch wipers into their second positions. In this position, primary magnet 110 and escape magnet 117 are maintained energized over a circuit extending from grounded battery, winding of primary magnet 110, winding of escape magnet 117, side-switch wiper 118 in position 2, side-switch wiper 114 in position 2, left-hand armature and front contact of relay 109, right-hand armature and front contact of relay 108 to ground. A circuit is now closed for the secondary stepping magnet 112 extending from grounded battery, winding of magnet 112, side-switch wiper 111 in its second position, back contact and armature of magnet 112, right armature and front contact of escape magnet 117, right armature and back contact of release magnet 113, side-switch wiper 114 in its second position, left armature and front contact of relay 109, right armature and front contact of relay 108 to ground. This stepping circuit for the secondary magnet 112 is maintained until the brushes 119, 120 and 121 of the line finder B engage the terminals 122, 123, 124 of the calling subscriber's line. When so engaged, a circuit is completed for cut-off relay, 101, extending from grounded battery, winding of relay 101, terminal 122, brush 119, left armature of escape magnet 117, resistance 127, side switch wiper 114, left-hand armature and front contact of relay 109, right-hand armature and front contact of relay 108 to ground. Relay 101 energizes and breaks the locking circuit for relay 108 at the outer armature and back contact of said relay 101. Relay 108 releases and opens the circuit for escape magnet 117 which deenergizes and moves the side-switch wipers into position 3. Cut-off relay 101 remains energized in this position of the side switch over a circuit extending from grounded battery, winding of relay 101, terminal 122, brush 119, contact spring 125, contact 126, left armature and back contact of release magnet 113 to ground.

Assuming that the subscriber at the substation A had not operated the impulse sending device C previous to the movement of the side-switch wipers of the line finder switch B to their third positions, the movement of the wipers 128 and 129 to such position will extend the calling subscriber's line to the first selector switch D, at which time a circuit will be closed for line relay 200 of said selector switch extending from grounded battery, left winding of relay 200, resistance 201, side-switch wiper 202 in position 1, the lower side of the telephone line, substation apparatus A, sending device C, conductor 102, contacts 103, conductor 104, upper side of the telephone line, side-switch wiper 203, and right winding of relay 200 to ground.

However, should the subscriber at substation A manipulate the dial of the sending device C previous to the movement of wipers 128 and 129 to position 3, contacts 103 at said sending device will be opened and the resistance 130 included in the subscriber's line. Relay 100 will, however, continue to be energized and the line finder switch will operate to connect the calling line with selector switch D, at which time the two resistances 130 and 201 will be in series. Relay 200 is so adjusted that the same will not energize when these resistances are in series and consequently the selector switch will fail to respond to impulses transmitted from the sending device C. It will, therefore, be apparent that the set of impulses designed to operate the selector switch D will be lost and succeeding impulses for operating the other switches will fail to establish a connection to terminals leading to the called line.

Now, assuming again that the sending device at substation A was properly operated and that relay 200 of the selector switch D became energized upon movement of the side-switch wipers 128, 129 to position 3, energization of relay 200 will close a circuit for slow-to-release relay 204 extending from grounded battery, winding of relay 204, front contact and armature of relay 200 to ground, and relay 204 will become energized. It is to be noted that during the operation of the sending device, resistance 130 will be included in the circuit with resistance 201 until switch D is stepped from normal but relay 200 is so adjusted that the same will not release when said resistances are in series. The switch is now in position to receive the first series of impulses transmitted from the sending

- device at substation A and in response to each impulse, line relay 200 will be momentarily deenergized. Upon each deenergization, a circuit will be closed from grounded 5 battery, winding of primary stepping magnet 205, contact 206, front contact and armature of relay 204, back contact and armature of relay 200 to ground. The first deenergization of line relay 200 and the con- 10 sequent stepping of the switch by the operation of magnet 205, will close the off-normal contact 216 and thus provide a shunt for the resistance 201, which will permit energization of relay 200, since only the re- 15 sistance 130 is now included in the line circuit, while the sending device C is operated. A circuit is also completed for slow-to-release relay 207 extending from grounded battery, winding of relay 207, front con- 20 tact and armature of relay 204, back contact and armature of relay 200 to ground. Energization of relay 207 completes a circuit from grounded battery, winding of escape magnet 208, side-switch wiper 209 in posi- 25 tion 1, armature and front contact of relay 207 to ground. Relays 204 and 207 being slow to release, will maintain their armatures attracted during the transmission of impulses to relay 200. At the termination 30 of the first series of impulses, relay 200 remains energized for a sufficient length of time to permit deenergization of relay 207 and upon its release, escape magnet 208 will deenergize and move the side-switch 35 wipers into position 2. In this position, a circuit will be closed for secondary stepping magnet 210 extending from grounded battery, winding of said magnet, armature and back contact thereof, side-switch wiper 40 211 in position 2, front contact and armature of relay 200 to ground. Magnet 210, being self-interrupting, will step brushes 212, 213 and 214 over the terminals of the selected group until an idle trunk leading 45 to the connector switch E is found, the idle condition of this switch being denoted by a ground upon the test terminal 215. As soon as brush 212 engages terminal 215, a circuit will be closed for escape magnet 208 50 extending from grounded battery, winding of said magnet, side-switch wiper 209 in position 2, brush 212, terminal 215, left armature and back contact of relay 300 of the connector switch, back contact and right 55 armature of slow-to-release relay 301, back contact and armature of line relay 302 to ground. Escape magnet 208 energizes and moves the side-switch wipers of the selector switch D into position 3. 60 It the subscriber at substation A should operate his sending device previous to the seizure of the trunk leading to connector switch E, contacts 103 will again be opened and resistance 130 included in the line cir- 65 cuit. Upon movement of the side-switch
- wipers 202 and 203 into position 3, a resistance 303 associated with line relay 302 of the connector switch will be placed in series with resistance 130 and said line relay will fail to energize, with the result 70 that the second set of impulses intended to step the connector switch will be lost and said switch will remain in its normal position.
- Assuming that the operator at substation A did not operate his sending device before the trunk leading to connector switch E was seized, the movement of side-switch wipers 202 and 203 into position 3 will extend the line to said connector switch. A 75 circuit is then completed from grounded battery, right winding of line relay 302, lower side of the telephone line, substation apparatus A, conductor 102, contacts 103, conductor 104, upper side of the telephone line, resistance 303 and left winding of relay 302 to ground. Energization of relay 302 closes a circuit for slow-to-release relay 301 extending from grounded battery, 80 winding of said relay, front contact and armature of relay 302 to ground. The connector switch is now in condition to receive the second series of impulses. After the dial of sending device C has been initially 85 adjusted but before the first impulse is 90 transmitted, resistances 130 and 303 are in series, but relay 302 is adjusted so that the same will not release when this condition exists.
- In response to each impulse of this series, 100 line relay 302 is momentarily deenergized and thereby completes a circuit for primary stepping magnet 304 extending from grounded battery, winding of said magnet, side-switch wiper 305 in position 1, front contact and right armature of relay 301, back contact and armature of relay 302 to ground. A circuit is also completed for slow-to-release relay 306 extending from 105 grounded battery, winding of said relay, front contact and right armature of relay 301, back contact and armature of relay 302 to ground. Relays 301 and 306 being slow-to-release, will be maintained energized during 110 the transmission of the set of impulses. Energization of relay 306 establishes a circuit extending from grounded battery, front contact and right armature of relay 306, winding of escape magnet 307, back contact and armature of marginal relay 308 to 115 ground. Upon the first step of the connector switch, off-normal contacts 309 and 310 will close and the latter contact will shunt the resistance 303 so that the same will not be in series with the resistance 130 at substation A during the transmission of impulses. In response to the second set of impulses the connector switch will be stepped to the selected group of terminals and at the 120 termination of the impulses, line relay 302 125
- Upon movement of the side-switch

will remain energized, thereby causing the deenergization of slow-to-release relay 306. Release of relay 306 will open the circuit for escape magnet 307, which, upon releasing, will move the side-switch wipers of the connector switch into position 2.

The third set of impulses will again vibrate the armature of line relay 302 and cause energization of relays 301 and 306 and escape magnet 307, as previously described. A circuit is also closed for the secondary stepping magnet 311 extending from grounded battery, winding of magnet 311, side-switch wiper 305 in position 2, front contact and right armature of relay 301, back contact and armature of relay 302 to ground. Secondary magnet 311 operates to step the brushes 312, 313 and 314 on to the terminals 315, 316 and 317 individual to the telephone line associated with the called substation F. Should the called line be busy, a ground will be found upon test terminal 315. If this line is busy as a called line, this ground will be connected through side-switch wiper 318 in position 4 and brush 312 of some other connecting switch, or if busy as a calling line, ground will be connected through the left armature and back contact of release magnet 113, make-before-break contact 126, contact spring 125 and brush 119 of a line finder B connected thereto. Therefore, when relay 306 deenergizes after the third series of impulses, a circuit will be completed for release magnet 321, which may be traced from grounded battery, right winding of release magnet 321, right armature and back contact of relay 300, off-normal contact 309, left armature and back contact of relay 306, side-switch wiper 318, brush 312 and terminal 315 to ground. Release magnet 321 establishes a holding circuit for itself extending from grounded battery, winding of release magnet 217, off-normal contact 218 which was closed upon the first step of the selector switch D, side-switch wiper 219 in position 3, brush 212, terminal 215, left armature and front contact of relay 301, front contact and left armature of magnet 321 and left winding of said magnet to ground. Since escape magnet 307 is made slow to release, the circuit for release magnet 321 will be established before the side-switch wipers of the connector switch move into position 3. Energization of release magnet 321 permits the connector switch to return to its normal position in the well known manner. The release magnet 321 at its right armature and front contact connects the busy tone apparatus 322 to the lower side of the line circuit and thereby notifies the calling subscriber that the called line is busy. The establishment of the previously described holding circuit for release magnet 321 energizes release magnet 217 of selector switch D and

causes this switch to return to normal, at which time the off-normal contact 218 will be opened. A circuit is also established in parallel with magnet 217 extending from grounded battery, winding of release magnet 113 of line finder B, off-normal contacts 131, armature and back contact of relay 107, side-switch wiper 219 in position 3, brush 212, terminal 215, left armature and front contact of relay 301, front contact and left armature of release magnet 321, and left winding of said magnet to ground. Energization of the release magnet 113 returns the line finder switch D to normal position in a manner well known in the art. If the called line leading to substation F had been idle at the time the brush 312 engaged terminal 315, no ground would have been found on said terminal so that deenergization of relay 306 would have caused the release of escape magnet 307 and the side-switch wipers of the connector switch would have been moved into position 3.

In position 3, a circuit is completed from grounded battery, winding of relay 306, side-switch wiper 305, in position 3, front contact and armature of relay 302 to ground. Relay 306 energizes and again establishes the energizing circuit for escape magnet 307, which in attracting its armature, completes a circuit from a ringing generator (not shown), front contact and armature of escape magnet 307, winding of marginal relay 308, side-switch wiper 319 in position 3, brush 313, terminal 316, apparatus at substation F, terminal 317, brush 314, side-switch wiper 320 in position 3, front contact and armature of relay 302 to ground. The current flowing through this circuit is not sufficient to operate marginal relay 308 at this time, but as soon as the subscriber at substation F removes his receiver from its switchhook, thereby shunting the ringer at this substation, sufficient current flows through the marginal relay 308 to cause it to attract its armature and open the circuit of escape magnet 307. This escape magnet deenergizes and moves the side-switch wipers into position 4.

A connection has now been established between substations A and F, and talking current is supplied to the called subscriber's line from grounded battery, left winding of relay 300, side-switch wiper 319, brush 313, terminal 316, substation apparatus F, terminal 317, brush 314, side switch wiper 320 and right winding of relay 300 to ground.

At the termination of conversation the subscribers at substations A and F will, by replacing their receivers, deenergize line relays 300 and 302. Release of relay 302 causes in turn the deenergization of slow-to-release relay 301. Ground is then connected to the release conductor 323 through the armature and back contact of relay 302, 130

right armature and back contact of relay 301, back contact and left armature of relay 300. Circuits for release magnets 113, 217 and 321 are then completed over the conductor 5 323 and the respective switches associated with these release magnets will be returned to normal, as previously referred to.

What is claimed is:

1. In an automatic telephone exchange 10 system, a calling subscriber's line, an impulse sending device thereat, means for extending said calling subscriber's line, a switch for connecting said calling subscriber's line with the last named means and resistances at said sending device and said extending means operable to prevent actuation of the latter if said extending means is connected to the sending device while said sending device is operating.

2. In an automatic telephone exchange 20 system, a calling subscriber's line, an impulse sending device thereat, means for extending said calling subscriber's line, a switch for connecting said calling subscriber's line with the last named means, variably adjustable means for operating said sending device to control the operation of said extending means and resistances at said sending device and said extending means operable to prevent actuation of the latter if 30 said extending means is connected to the sending device while said sending device is operating.

3. In a telephone system, a telephone line, 35 a sender therefor, a numerical switch, means for automatically extending said line to said switch upon the initiation of a call therein, and means for preventing said numerical switch from responding to the first set of 40 impulses from said sender, said means being rendered effective only in case said numerical switch is connected to the sender while the sender is operating.

4. In a telephone system, a telephone line, 45 a dial therefor, a numerical switch, means for automatically extending said line to said switch upon the initiation of a call therein, and means for preventing said numerical switch from responding to the first set of 50 impulses from said dial, said means being rendered effective only in case said numerical switch is connected to said dial while the dial is operating.

5. In a telephone system, a telephone line, 55 a sender therefor, a numerical switch, a progressively movable non-numerical switch for automatically extending said line to said numerical switch upon the initiation of a call in said line, and means for preventing 60 said numerical switch from responding to the first set of impulses from said sender,

said means being rendered effective only in case said numerical switch is connected to said sender while the sender is operating.

6. In a telephone system, a subscriber's 65 line, a dial thereat, a selector, an automatic finder switch for extending said line to said selector upon the initiation of a call, and means rendered effective in case the selector is connected to the dial while the dial is off- 70 normal for preventing the corresponding set of impulses from affecting the selector.

7. In a telephone system, a telephone line, 75 a selector, groups of trunks terminating in numerical switches, a sender associated with said line, said selector being controlled by the initial set of impulses transmitted by said sender to select a group of trunks, means for causing said selector to select an idle trunk in said selected group, and means 80 for preventing the numerical switch in which said idle trunk terminates from responding to the succeeding set of impulses, said means being rendered effective in case said telephone line is extended to the said 85 numerical switch while said sender is operating.

8. In an automatic telephone exchange 90 system, a calling subscriber's line, an impulse sending device, a selector switch, for extending said line, an impulse relay for said selector switch, a switch for interconnecting said calling subscriber's line with said selector switch and resistances operable to prevent actuation of said relay in 95 response to the first set of impulses from said sending device, said resistances being rendered effective only in case said selector switch is connected to said sending device while the sending device is operating. 100

9. In an automatic telephone exchange 105 system, a calling subscriber's line, a sending device, a selector switch for extending said line, an impulse relay for said selector switch, a switch for interconnecting said calling subscriber's line with said selector switch, variable adjustable means for operating said sending device to control the operation of said selector switch and resistances associated with said sending device 110 and said selector switch to prevent actuation of said relay in response to the first set of impulses from said sending device, said resistance being rendered effective only in case said selector switch is connected to said sending device while the sending device is operating. 115

In witness whereof, we hereunto subscribe our names this 12th day of December A. D., 1918.

HENRY P. CLAUSEN.
CHARLES L. GOODRUM.
